PLYWOOD AND METHOD OF FORMATION

Ericsson H. Merritt, Lockport, N. Y., assignor, by
mesne assignments, to Laminating Patents
Corporation, Seattle, Wash., a corporation of
Delaware

Application January 18, 1932, Serial No. 587,217

10 Claims. (Cl. 154—2)

This invention relates to plywood and to methods of forming the same, and, more particularly, to plywood embodying insulating board and methods for its formation.

5 An object of the invention is the provision of an improved laminated product comprising a veneer facing backed by structural insulation.

A further object is to provide a product of the character described which is especially resistant 10 to marginal injury.

A still further object is to provide such a product which is sturdy and can be readily put in place.

15 Another object is the provision of an improved method of forming a product of the character under consideration.

A further object is to provide an improved method for uniting insulating board with natural wood.

20 A still further object is to provide a method for securing a strong bond between wood and a layer composed of materials of greater absorbent qualities.

Other objects of the invention will in part be 25 obvious and will in part appear hereinafter.

The invention accordingly comprises the several steps and the relation and order of one or more of such steps with respect to each of the others, and the article possessing the features, properties, and the relation of elements, which are exemplified in the following detailed disclosure, and the scope of the application of which will be indicated in the claims.

For a fuller understanding of the nature and 35 objects of the invention reference should be had to the following detailed description taken in connection with the accompanying drawings, in which:

Figure 1 is a top view of a section of plywood embodying the invention, with a portion of the 40 face veneer cut away;

Fig. 2 is a sectional view along the line 2—2 in Fig. 1;

Fig. 3 is a similar view of a two-ply structure;

Fig. 4 is a view similar to Fig. 1 showing a modified form of structure;

Fig. 5 is a sectional view along the line 5—5 in Fig. 4;

Fig. 6 is a top view showing another modification;

Fig. 7 is a sectional view along the line 7—7 in Fig. 6;

Fig. 8 is a diagrammatic showing of a method of forming plywood in accordance with the invention; and

Fig. 9 is an enlarged detail plan view of a corner of the lamination of Fig. 8 containing insulating board.

Structural insulating members composed of loose-textured material are well known and are 5 available in a variety of forms. Among these are boards comprising shreds, fibers or other types of particles of wood, of various straws, of roots and the like, and other loose-textured composite boards having the heat and sound insulating 10 qualities desirable for structural work. For the sake of facility of expression the term "insulating board" is used herein to describe such products.

The use of such products faced by natural 15 wood veneer has numerous advantages in constructional work where insulation and appearance are both required, as, for example, in the rooms of dwellings, and numerous efforts have been made to provide a material of this type which will satisfy the requirements for such 20 a product. Many difficulties have been encountered, however. Among these have been failure to secure a proper bond between the veneer and the insulating board, weakness in the marginal edges, and particularly in the corners of the 25 product, tendency toward cleavage along a plane parallel to the face of the product, and the fragility of the product when compared with natural wood.

With a view to overcoming the foregoing and 30 other difficulties, the invention contemplates the provision of a laminated product including a layer of reinforced insulating board and the provision of an improved method of uniting an insulating board-containing layer to a veneer facing. 35

In accordance with the invention there is provided a plywood structure comprising a layer composed principally of insulating board reinforced by sections of a dense material of the 40 nature of wood. Examples of such a material are natural wood and artificial woods having similar characteristics, for instance, boards formed from fibre or pulp and having a hard, dense structure imparted by relatively high pressure or otherwise. The reinforcing sections preferably extend transversely of the insulating board layer, i. e. from the front to the back thereof. The insulating board layer is faced and, preferably, also backed by a layer of veneer.

One example of a product such as contemplated 50 by the invention is exemplified in Figs. 1 and 2. This product comprises a core 10, the major portion of which is composed of sections 11 of insulating board with internal and marginal reinforcing members 12 and 13, respectively, of 55

natural wood or the like. On either side of this core are facings 14 and 15 of veneer suitably united with the core by an adhesive.

In instances where the veneer backing is unnecessary, this may be omitted as indicated in Fig. 3, wherein there is shown a veneer facing 16 secured to a reinforced insulating board layer 17, which is in this instance, constructed similarly to the layer 10 of Figs. 1 and 2. It may be noted in this connection, however, that when face and back veneers are utilized, a particularly sturdy product is secured.

There is shown in Figs. 4 and 5 a construction somewhat similar to that shown in Fig. 1. In this instance only the parallel reinforcing portions of natural wood are utilized, the lateral members being omitted. The insulating board layer is indicated at 18, the parallel reinforcing members at 19 and the veneer facing and back at 20 and 20'.

It is to be noted that in each of these cases reinforcement is provided at the corners of the panel. In some instances the reinforcing members may be omitted at all portions of the insulating board layer except the corners. A structure of this nature is shown in Figs. 6 and 7 wherein the insulating board layer is shown at 21 as embodying triangular reinforcing members 22 of natural wood or the like at each corner. The veneer facing and back are indicated at 23 and 23'.

As will be understood, the reinforcing members may be arranged in numerous other ways without departing from the invention.

Due to the provision of reinforcing members, as indicated, it is possible to provide a structure which stands substantially the same stresses as a solid wood panel and will possess additional insulating properties. Moreover, the wood sections are particularly adapted for easy nailing. Such a product, because of its rigidity, can be applied directly to the studding of a house and provide protection against heat, cold and sound, and at the same time form a smooth surface which can be readily finished with paint or varnish. In such a panel, the tendency toward peeling, which is particularly marked when paint or varnish are applied to a surfacing veneer due to the strains set up, is greatly reduced where the face and back veneers are tied together by the reinforcing means.

In the formation of a panel including a layer of insulating board, the use of liquid glues has various disadvantages, among which is the excessive tendency of insulating board to absorb glue, and, when these contain a strong alkali, its tendency to attack the size and/or the cellulose fibres themselves, and to increase the absorbent action thereof. To avoid these and other difficulties the invention contemplates the application of an adhesive base in powdered form to a surface to be glued. Any of a wide variety of types of adhesive may be utilized, reference being made particularly to powdered casein, soya bean flour and powdered blood albumin, the latter being particularly desirable.

With a view to securing a particularly strong bond between the insulating layer and the veneer, the invention contemplates the pre-treatment of the reinforcing members. Such pre-treatment preferably comprises applying to one or more of the surfaces thereof a bond-assisting liquid. Such liquid may comprise a heat-setting liquid glue, for instance, a wet blood glue, or a suitable bond-assisting chemical such, for exam-

ple, as caustic soda in cases where proteinous adhesives such as those mentioned above are to be utilized.

In the use of an adhesive, for instance those mentioned above, of a character such that the plasticization thereof may be assisted by an alkaline reagent, a mild alkaline reagent may be provided at the glue line and a particularly strong alkaline reagent may be provided at the portion of the glue line where wood contacts with wood. The mild alkaline reagent may be desirably supplied by mixing powdered lime with the adhesive before application, and the strong alkaline reagent may be desirably supplied by dipping the reinforcing inserts in a solution of caustic soda or other strong alkali before association with the insulating section or sections, or by painting their surfaces after inclusion. Either reagent may be applied in any other suitable manner.

In the use of an adhesive plasticizable by water, moisture may be provided in any suitable manner, as from one or the other of the layers if these contain sufficient water to yield up a supply to the adhesive, or by spraying one or both of the surfaces to be glued before and/or after the application of the powdered adhesive.

A specific form of procedure whereby articles embodying the invention may be produced and a method embodying the invention may be carried out is illustrated in Fig. 8. The reinforcing inserts are carried through a tank 24 containing a caustic soda solution indicated at 25 by means of a conveyor 26. Preferably, in the construction of articles such as shown in Figs. 1 and 2, the inserts are formed into a framework as indicated at 27 and thus pass through the treating bath. Parallel to the conveyor 26 is a conveyor 28 on which veneer plies 29 are carried under material applying mechanisms indicated diagrammatically at 30, 31 and 32. The mechanisms 30 and 32 are indicated diagrammatically as a type disclosed in the copending application of Ericsson H. Merritt and Richard W. Stanley, Serial No. 535,822, filed May 8, 1931, and the mechanism 31 is indicated diagrammatically as of the type disclosed in the copending application of Louis G. Merritt and Ericsson H. Merritt, Serial No. 542,257, filed June 5, 1931. By this means the upper surfaces of the veneer plies are first moistened, after which there is applied powdered blood albumin with which hydrated lime has been admixed in a proportion of about one part by weight of hydrated lime to three parts by weight of blood albumin, and the powder is thereafter moistened by the mechanism 32. The pre-treated frame 27 is disposed on a veneer ply 29, after it has passed under the mechanisms 30, 31 and 32, and insulating board sections 33 are associated with the frame to complete the layer. A succeeding veneer ply 29 is turned over and placed upon the layer 34 formed by the members 33 and the frame 27. The completed assembly is thereafter subjected to bonding conditions, for example, to a pressure of 150 lbs. per square inch at 250° F. for about thirty seconds, in a suitable veneer press such as indicated diagrammatically at 35.

In accordance with the procedure such as the foregoing, there may be efficiently produced a product wherein veneer is effectively united to both the insulating board and the natural wood sections and wherein neither splitting of the veneer nor deformation of the insulating board portions occur.

Since certain changes in carrying out the above

method, and certain modifications in the article which embody the invention may be made without departing from its scope, it is intended that all matter contained in the above description or 5 shown in the accompanying drawings shall be interpreted as illustrative and not in a limiting sense.

It is also to be understood that the following 10 claims are intended to cover all of the generic and specific features of the invention herein described, and all statements of the scope of the invention which, as a matter of language, might be said to fall therebetween.

Having described my invention, what I claim as 15 new and desire to secure by Letters Patent is:

1. The method of forming plywood, which comprises applying a facing layer to a layer composed principally of insulating board and containing sections of a dense material of the nature of wood, and subjecting to bonding conditions 20 in the presence of an interposed adhesive in powdered form, said method including the step of pre-treating in a predetermined manner the wood sections of the insulating board layer 25 with a bond assisting liquid prior to contacting the adhesive therewith, said insulating board not being so pre-treated.

2. The method of forming plywood, which comprises forming a layer composed principally of 30 insulating board and having incorporated therein sections of a dense material of the nature of wood, the surfaces of said sections aligned with the insulating board surface to be glued having been pre-treated with a bond-assisting liquid, 35 providing a veneer layer, applying an adhesive in powdered form to the surface of one of said layers, assembling and subjecting to bonding conditions.

3. The method of forming plywood, which comprises forming a layer composed principally of 40 insulating board and having incorporated therein sections of a dense material of the nature of wood, the surfaces of said sections aligned with the insulating board surfaces to be glued having 45 been pre-treated with a bond-assisting liquid, providing veneer layers, applying an adhesive in powdered form to at least one of each pair of surfaces to be united, assembling and subjecting to bonding conditions.

4. The method of forming plywood, which comprises applying a layer of veneer to a layer composed principally of insulating board and containing sections of a dense material of the 50 nature of wood, and subjecting to bonding conditions, said method including the step of applying to at least one of the surfaces to be joined a powdered adhesive material of such character that the plasticization thereof is assisted by an alkaline re-agent, and the step of applying a strong 55 alkali having the alkalinity of a strong solution

of caustic soda, to the surfaces of said wood sections.

5. The method of forming plywood which comprises dipping in a caustic soda solution inserts 5 formed of a dense material in the nature of wood, forming a layer composed principally of insulating board and including said wood inserts, providing a veneer layer, applying to one of said layers an adhesive base in powdered form, assembling and subjecting to bonding conditions. 10

6. The method of forming plywood, which comprises dipping in a caustic soda solution inserts 15 formed of a dense material in the nature of wood, forming a layer composed principally of insulating board and including said wood inserts, providing a veneer layer, applying to said veneer layer a powdered adhesive base which is of such character that the plasticization thereof is assisted by caustic soda and which is heat-coagulable, assembling and subjecting to heat and pressure. 20

7. The method of forming plywood, which comprises dipping in a caustic soda solution inserts 25 formed of a dense material in the nature of wood, forming a layer composed principally of insulating board and including said wood inserts, providing a veneer layer, applying to one of said layers powdered blood albumin admixed with hydrated lime in a proportion of about one part of hydrated lime to three parts of blood albumin, 30 assembling and subjecting to heat and pressure.

8. A method of forming plywood, which comprises providing a core composed principally of insulating board with transversely-extending inserts 35 of a dense material of the nature of wood, providing a veneer facing, utilizing an adhesive base of a character such that the plasticization thereof in the presence of water is facilitated by an alkaline reagent, providing an alkaline reagent for the adhesive base, providing a stronger alkaline reagent for the adhesive base at said inserts, assembling and subjecting to bonding conditions. 40

9. A method of forming plywood, which comprises applying an adhesive base in powdered 45 form to a surface of each of a pair of veneer facings, forming on one of said surfaces a core of insulating board having transversely-extending inserts of a dense material of the nature of wood pre-treated with a bond-assisting liquid, disposing 50 the other of said surfaces thereupon, and subjecting to bonding conditions.

10. The method of forming plywood, which comprises applying an adhesive base in powdered 55 form to a surface of a veneer facing, forming a core of insulating board having transversely-extending inserts of a dense material of the nature of wood pre-treated with a bond-assisting liquid, disposing said surface thereupon and subjecting to bonding conditions. 60

ERICSSON H. MERRITT.
